This technical drawing illustrates a vertical filter press assembly. The central component is a rectangular frame 200, which is supported by a vertical post 210. The frame 200 contains a series of vertical filter cloths 204. A horizontal plate 202 is positioned above the cloths 204. On the left side, a vertical cylinder 215 is connected to a horizontal pipe 214, which is secured to the frame 200. On the right side, a vertical cylinder 218 is connected to a horizontal pipe 216, which is secured to the frame 200. The base of the frame 200 is supported by a foundation 206. A vertical pipe 208 is shown on the right side, with an arrow indicating an upward flow direction.

PROCESS FOR COUNTERCURRENT WASHING OF COOKING LIQUOR OUT OF PULP

Elmer R. Burling and John P. Rich, Nashua, N. H., assignors to Improved Machinery, Inc., Nashua, N. H., a corporation of Maine

Application October 22, 1953, Serial No. 387,694

4 Claims. (Cl. 8—156)

The present invention relates to a new use of pulp thickeners generally of the type disclosed in Patent Nos. 1,816,132 and 2,537,414, and others of a similar nature.

Filters of the type above mentioned operate under a low vacuum head and the vacuum is internally generated by the rotation of the filter drum. Such filters have been in use for many years but only as thickeners or dewaterers, or as in individual washers.

Within the pulp and paper industry heretofore counter-current washing of pulp for the removal and recovery of, say, cooking liquors has been done on countercurrent washing principles by numerous methods but most frequently by a series of open cylinders or high vacuum filters. Wash liquor, applied by means of showers, has been drawn through the pulp as it travels around the drum. The liquor drawn through each drum is collected in a tank and used as a shower on the next preceding drum and as repulping liquor to prepare a slurry from the thickened pulp leaving the preceding drum to make it ready for the washing action of the next drum. In these vacuum installations for best operation the level of liquor in the tanks receiving the liquor from each drum must be from 25 to 38 feet below the center line of the drum from which the tank receives the liquor in order that efficient vacuum may be maintained or else vacuum pumps must be used. In this relatively great fall the liquor tends to be thoroughly mixed with entrained air to form a foam. One compensation for this to deaerate the liquor is greatly to increase the size of the liquor receiving tank. Moreover since the liquor received in the tank must be pumped again to at least the center line level of the drum, pumping costs are very heavy indeed. This foaming tendency is more pronounced where alkaline cooking liquors are involved since such liquors saponify the fatty acid content of the wood.

The present invention, using the low head internally generated vacuum permits the tanks and their liquor level to be placed a minimum distance below the center line of the drum. There is less agitation of the liquor and consequently less foam so that the tanks, in order to handle the same amount of liquor, need be only about $\frac{1}{3}$ the size of the tanks in conventional high vacuum washing. Moreover the pumping head is very greatly reduced. This latter factor will be appreciated when it is realized that for every 100 tons of pulp, at least 5000 tons of liquor must be pumped for each stage of the washing. Moreover, the internally generated vacuum permits the use of much larger discharge pipes than are tolerable in a high vacuum system. Obviously the use of larger diameter discharge pipes reduce the velocity and therefore the turbulence within the pipes.

It is an object of this invention to provide a process for the countercurrent washing of pulp which may be carried out in far less plant cubic footage than conventionally now used, and/or at greatly reduced capital investment and/or at greatly reduced operating cost.

The above and other objects will be made clear from

2

the following detailed description taken in connection with the annexed drawings, in which:

Figure 1 is a schematic diagram of a four-stage washing installation;

Figure 2 is a plan view showing a somewhat different relationship between the washers and the receiving tanks;

Figure 3 is a view similar to Figures 1 and 2 but showing an arrangement for the elimination of repulpers between the washers;

Figure 4 is a radial section through one of the washers showing the means by which rotation of the drum generates the vacuum;

Figure 5 is a longitudinal section through a washer and its associated tank and illustrating control of foaming conditions; and

Figure 5A schematically illustrates the connections between the unit of Figure 5 and a foam breaker system;

Figure 6 is a view similar to Figure 5 but showing a somewhat different relationship between the tank and the washer.

Figure 6A schematically illustrates the connection between the arrangement of Figure 6 and a foam breaker system.

Referring now to Figure 1 there are shown drums A, B, C and D rotating, respectively, in vats A', B', C' and D'. Liquor extracted by drum A passes through a line 2 into a tank A''. Liquor from drum B goes through a line 4 to a tank B''. Liquor from drum C goes through a line 6 to a tank C'' and liquor from drum D goes through a line 8 to a tank D''. Pulp from the drum A is removed by a doctor 10 to a repulper 12 whence it goes to the vat B' and is drawn onto the drum B. A doctor 14 removes the pulp layer from the drum B and delivers it to a repulper 16 whence it goes to the vat C' and is drawn onto the drum C. A doctor 18 removes the pulp layer from the drum C and delivers it to a repulper 20 whence it goes to the vat D' where it is drawn onto the drum D. A doctor 22 removes the pulp from the drum D and delivers it to a repulper 24 whence it goes to other processing

40 through a line 26.

A fresh water line 28 has one branch 30 feeding the final repulper 24 and another branch 32 feeding a shower pipe 34 directed against the face of the final drum D. A pump 36 removes liquor from the tank D'' and delivers it to the repulper 20 and to a shower 38 directed against the face of the drum C. A pump 40 removes liquor from the tank C' and delivers it to the repulper 16 and to a shower 42 directed against the face of the drum B. A pump 44 removes liquor from the tank B'' and delivers it to the repulper 12 and also to a shower 46 directed against the face of the drum A. A line 48 delivers the pulp, in its original strength liquor, to the vat A' where it is drawn upon the surface of the drum A. A pump 50 removes liquor from tank A'' and delivers it to the recovery system.

55 It is to be noted that each of the tanks A'', B'', C'' and D'' is directly below its respective washing unit so that in effect the walls of the tank form the vertical foundation of the washing unit and the washing unit acts substantially as a lid for the tank. This extremely compact relationship is impossible of accomplishment with conventional high vacuum washing. It is clear that the head against which the pumps 36, 40 and 44 must operate is greatly reduced over conventional practice and their power consumption is accordingly equally reduced.

60 In Figure 2 the tanks A'', B'', C'' and D'' have about the same vertical relationship to the drums A, B, C and D as is shown in Figure 1. Instead of being placed under the drums, however, the tanks are offset to one side. Occasionally this is of advantage where an installation has to be fitted into an existing mill.

Figure 3 is a schematic representation of a special case. Here an initial drum E corresponding to drum A of Fig-

ure 1 rotates in a vat E' and delivers extracted liquor to a tank E'', whence the liquor is pumped by means (not shown) to the recovery system. A second drum F rotates in a vat F' and delivers extracted liquor to a tank F'' which is defined in part by an upwardly extending baffle 60. Liquor entering the tank F'' overflows the baffle 60 to an auxiliary tank 64 which is divided into two parts by a downwardly extending baffle 62. A pulp matte 70 is doctored off the drum E and falls into the left-hand compartment of the tank 64 where it is defibered by an agitator 68. The dilute defibered stock is picked up by a pump 71 and is delivered to the vat F'. A pump 72 through a line 74 delivers liquor from the tank F' to a shower 76 playing on the face of the drum E. The arrangement just described obviously can be repeated as often as required to carry out additional stages of washing.

This arrangement eliminates the pumping cost of returning liquor to the conventional repulping operation and by conventional practice this is a very much larger proportion of liquor than is delivered to a shower such as 76.

Referring now to Figure 4 there is shown for the purpose of completing this disclosure an extremely simplified transverse cross-section of one of the filters. Here a foraminous drum 100 is divided into axially extending compartments 102. Showers 104 are directed against the surface of the drum 100. Each compartment 102 has a bottom orifice 106 communicating with a circumferential channel 108 having a discharge opening 110. As the drum rotates in the direction of the arrow 112, successive compartments 102 encounter a doctor 114 which delivers pulp to a repulper 116. The compartments then enter a vat 118 to which a pulp slurry is fed from a preceding repulper 120 or other source of supply. Liquor immediately begins to flow from the vat 118 into each of the compartments 102 thence through the openings 106 to the channels 108 and then through the openings 110 into the interior of the drum. A certain layer of pulp is thereby built up on the exterior of the drum 100 by the hydrostatic pressure of the slurry in the vat 118. Because the effective head is limited to the rather small differential between the interior and exterior of the drum the initial web formed on the drum is low density uncompacted stock.

As each compartment continues to rotate, there comes a time when its orifice 106 arises above the level of stock in the vat 118, but since, in this region, the exit orifice 110 of the channel 108 is still submerged, a vacuum is created tending to suck shower water from the pipes 104 through the pulp matte. When the channel exit 110 finally rises above the liquor level inside the drum the vacuum is broken and the pulp thereupon is ready to be removed by the doctor 114.

From the foregoing it will be clear that the only vacuum action or sucking action is occasioned internally by rotation of the drum and not by the application of any external source of sub-atmospheric pressure such as a vacuum pump or barometric leg. This is the basis of the two above identified patents.

It is most difficult to explain precisely why a piece of equipment should remain available to the industry for more than 20 years and yet be put only to the limited use of dewatering pulp whereas when the same equipment is applied to countercurrent washing it produces enormous advantages over the equipment theretofore used for such purposes. Probably it was the consensus of opinion in the industry that only a high vacuum would serve both to draw the initial liquor out of the pulp and also to draw through the pulp the requisite shower water, though this must forever remain a matter of conjecture. What actually appears to be the fact however is that the low vacuum of the valveless washer produces a freer, less dense formation of pulp on the drum and through such a formation the low vacuum is entirely adequate to draw the wash liquor. It is true that, due to the freer formation on the drum, more air may be drawn through the valveless

washer than is drawn through the conventional high vacuum washer but, since the travel of the commingled air and liquor is for a shorter distance, and with less intimate mixing than necessarily must be the case with the high vacuum washer, liquor drawn through the valveless washer suffers far less from volumetric increase due to foam and is far easier to deaerate than liquor drawn through the high vacuum washer.

Figures 5 through 6A, inclusive, deal with arrangements for still further minimizing from conditions in washers of the type the subject of this application. In this type machine, since the matte formed on the drum is less dense than that formed on the high vacuum washer, considerable air is drawn through with the liquor to the interior of the drum hence into the receiving tank. In some cases it may not be enough merely to vent the tank since there would have to be at least some above-atmospheric pressure in the system to cause the air to leave the vent and this might cause flow-back at the takeoff point on the drum and thus re-wet the washed sheet with liquor.

Referring now to Figure 5 there is shown a drum 200 in a vat 202. Liquor flows through one end 204 of the drum into a receiving tank 206. A pump 208 removes liquor from the tank 206 for re-circulation as above described. The end of the drum 210 opposite the end 204 is completely closed. At the liquid delivery end 204 the drum itself is completely open but the vat 202 is sealed to the drum by means of a deckle strap 212 and an end closure 214. The vat and tank are vented by a pipe 216 feeding a header 218. As shown in Figure 5A the header 218 may serve any number of washers and communicate through a duct 220 either with a foam tank 222 surmounted by a suction fan 224 or for the foam tank 222 and a suction fan 224 there may be substituted a combination suction fan and foam breaker. The result is to establish within each unit a slightly subatmospheric pressure, in the region of a few inches of water, which completely prevents any possible blowback and serves, moreover, as an excellent means for the extraction of foam from the system thereby permitting the receiving tank 206 to be made smaller than otherwise would be the case.

In operating on kraft black liquor where the saponification is high, there is a very considerable foaming tendency. When the liquor is drawn through the pulp matte and discharged from the interior of the drum to the receiving tank, the foam is heavy, hard to move and apparently generates its own pressure so much that at times, the foam tends to rise back into the drum. This foam, of course, could be moved by a vacuum into the foam-breaker but creation and maintenance of sufficient vacuum for this purpose would be uneconomical. There is need for a very slight vacuum within the drum in order to evacuate the entrapped air which comes through the pulp matte. There is also need for a slight vacuum to "bias" the flow of foam from the tank toward the foam-breaker and since the foam seems to create a pressure of its own, only a biasing vacuum is essential to direct the flow. To meet this specialized condition, we propose to apply substantially the same vacuum to the line running to the foam-breaker and also directly to the drum, the differential which serves to bias the foam being supplied by the foam's own independent pressure. By this means the foam is directed away from the drum and toward the foam-breaker while any blow-back tendency within the drum is completely avoided.

The effects described in the above paragraph are achieved in the form illustrated in Fig. 5 by the provision of a vacuum line 215 which penetrates the end closure 214 of the drum 200. The line 215 may connect to an independent vacuum source, or it may connect to the foam tank 222. In either case, however, blow-back within the drum 200 is completely avoided.

In Figure 6 the drum 200 and vat 202 with deckle strap 212 and tank end closure 214 in all respects identical with the arrangement of Figure 5. Here, however, a duct 226

delivers the effluent from the drum 200 horizontally to a tank 228 placed adjacent the washer. A vent 230 is provided in the top of the tank 228 and communicates with a fan and foam breaker 232 as shown in Figure 6A. When the foam breaker is used the liquor recovered from the foam is returned to the system and therefore represents neither a loss nor a threat to the efficiency of the system.

In Figures 6 and 6A a line 231 is shown connecting the end closure 214 to the fan and foam breaker 228. The line 231 serves the same purpose as the line 215 of Figure 5.

What is claimed is:

1. A process of washing residual, highly forming, cooking liquor out of pulp comprising: operating on counter-current principles a series of horizontal, foraminous cylindrical filters of the type wherein liquor is sucked inwardly through the foraminous surface of the cylinder wall under vacuum generated primarily as a result of rotation of the cylinder; separately collecting the liquor extracted by each filter; returning from each succeeding filter a portion of the liquor collected thereby as a shower on the face of the preceding filter; and using a portion of the remainder to dilute pulp concentrated on the preceding filter, the collection of liquor extracted by each cylinder occurring at a level only a little below the center line of such cylinder. 25

2. A process as set forth in claim 1 in which the liquor is stored in a reservoir at a level only a little below the center-line of the cylinder.
3. A process as set forth in claim 1 including the steps of delivering extracted liquor to the interior of the cylinder; draining said liquor from the interior of the cylinder to a collection vat and enforcing the maintenance of a slight subatmospheric pressure within the interior of said cylinder and said vat.
4. A process as set forth in claim 1 in which the interior of each filter and its liquor collecting means are maintained at slight subatmospheric pressure.
